UNITED STATES PATENT OFFICE.

OSCAR W. FAUSER, OF BELLEROSE, NEW YORK, ASSIGNOR TO CONGOLEUM-NAIRN, INC., A CORPORATION OF NEW YORK.

DESIGN FOR A RUG OR SIMILAR ARTICLE.

Application filed October 29, 1927. Serial No. 23,940. Term of patent 7 years.

To all whom it may concern:

Be it known that I, OSCAR W. FAUSER, a citizen of the United States, residing at 44 Hudson Road, Bellerose, in the county of Nassau and State of New York, have invented a certain new, original, and ornamental Design for Rug or Similar Article (Case #35), of which the following is a specification, reference being had to the accompanying drawing, forming a part hereof.

The figure is a plan view of a rug, showing my design.

I claim:

The ornamental design for a rug or similar article, substantially as shown.

In testimony whereof, I affix my signature.

OSCAR W. FAUSER.
